LOW TEMPERATURE SULFONATION PROCESS

Charles F. W. Gebelein, Butler, Pa., assignor to Esso Research and Engineering Company, a corporation of Delaware

No Drawing. Application September 9, 1955
Serial No. 533,503

3 Claims. (Cl. 260—504)

This invention relates to an improved low temperature process for the preparation of oil and water soluble sulfonates. More particularly it relates to an integrated process for the preparation and recovery of these differing sulfonates.

The sulfonation of petroleum oils to oil and water soluble sulfonates is well known. Recent work has shown that considerable quantities of the oil soluble derivatives are present in the acid sludge layer. This decreases the yields of the desired products. In addition it is known that oil soluble sulfonates are lost by degradation reactions including those which convert potential feed for oil soluble products to water soluble products. In some cases this loss has been found to be equivalent to between 50 and 100% of the oil soluble sulfonic acids recovered in the acid oil in the conventional manner. Furthermore co-solvency effects of the oil and water soluble sulfonates have prevented sharp separations in the stratifying procedures utilized. All of these factors have contributed to diminished yields.

The present invention provides an improved process for preparing and recovering high yields of oil and water soluble sulfonates free of the beforementioned difficulties. In brief summary, the process comprises treating a petroleum oil feed dissolved in liquid sulfur dioxide at low temperatures with a single treat of a sulfonating agent. The mixture is neutralized in the presence of a low alcohol. The crude alcoholic soap solution is then countercurrently extracted according to this invention with an organic solvent and the different type sulfonates recovered.

The invention will now be further explained in greater detail.

The petroleum hydrocarbon oil feed stocks can be utilized include feed stocks which may or may not have been previously acid treated, deasphalted, dewaxed or extracted with solvents such as ketones, nitrobenzene, phenol, cresol, chlorox, etc., or which may be a distillate, neutral or bright stock or mixture of these, but is still reactive with sulfuric acid. These feed stocks can be obtained from crudes which are either predominantly paraffinic or naphthenic in character, both of which contain appreciable proportions of aromatic constituents. Synthetic feeds can also be used such as C₁₂ polypropyl benzene alkylate bottoms and are intended to be included.

These oil feed stocks are known generically as lubricating oil fractions. Oils which are preferred for acid treating in the practice of this invention can vary in viscosity from about 100 to 2000 seconds Saybolt at 100° F. and thus usually boil in the range of about 315° to 600° C. as determined by vacuum Engler distillation corrected to atmospheric pressure.

In general the oil soluble sulfonic acids as described herein are those having the general formula RSO₃H, where the molecular weight of the R is greater than 230. The water soluble sulfonic acids as described herein connote di-sulfonic acids having the general formula

2

R(SO₃H)₂, where the molecular weight of R is less than 600.

The feed stock is dissolved in liquid sulfur dioxide, or other suitable diluents such as nitrogen, Freons (dichlorodifluoromethane and other halogenated hydrocarbons having more than one fluorine atom per molecule), butane, chloroform, etc. The ranges of hydrocarbon oil to sulfur dioxide utilized is in the range of 20 to 100 volume percent, preferably 70 to 100 volume percent. The pressure and temperature are maintained so as to keep the SO₂ in the liquid state.

The solution of petroleum oil feed in liquid sulfur dioxide is contacted with a sulfonating agent in a single treat, i. e., all at one time rather than in stages. The sulfonating agents that can be employed include from 15 100% sulfuric acid through various stages of fuming sulfuric acid containing, for example, 25% dissolved SO₃ or 65% dissolved SO₃ up to and including a stabilized liquid anhydrous SO₃ available commercially as "Sulfan B."

The amount of sulfonating agent employed for maximum oil soluble sulfonate production is dependent on the sulfonatable hydrocarbon concentration present in the feed stock. This may be conveniently determined in 25 a laboratory assay employing the herein described process conditions and an excess of acid. From the yield of total sulfonate and average molecular weight of the sulfonate and hydrocarbon feed stock the mols of sulfonatable hydrocarbons in the feed stock can be closely approximated. It is preferred to employ between 3 to 7 30 mols of SO₃ per mol of sulfonatable hydrocarbons for maximum oil soluble sulfonate production, when sulfuric acids or oleum are employed. When either gaseous or liquid SO₃ are employed it is preferred to use 1½ mols

35 to 3½ mols of SO₃ per mol of sulfonatable hydrocarbon. To obtain maximum yields of total sulfonate it is preferred to use 5 to 11 mols of SO₃ per mol of sulfonatable hydrocarbon when oleum or sulfuric acid are employed and 2.5 to 5½ mols of SO₃ per mol of sulfonatable hydrocarbon when liquid or gaseous SO₃ are employed. For maximum production of water soluble sulfonates this concentration may be increased to 30 to 45 mols of SO₃ per mol of sulfonatable hydrocarbon when oleum or sulfuric acid are used or 15 to 22½ mols of SO₃ per mol of 40

45 sulfonatable hydrocarbon when liquid or gaseous SO₃ are employed. The order of addition of reagents is critical for optimum yields of oil soluble sulfonate. The sulfonating agent, either alone or dissolved in liquid SO₂, should be added to the hydrocarbon feed stock solution 50 and not the reverse order of addition.

The temperature utilized for the sulfonation is kept by refrigeration at a maximum of 0° C. and preferably a maximum of -10° C. Usually 20 to 40 minutes are required to add the oleum followed by 30 to 60 minutes 55 additional agitation.

For purposes of carrying out the reaction a reaction vessel may be used containing a high-speed type of turbo or shear type of mixer containing means for heat exchange either through the walls of the reactor or by 60 means of cooling coils contained within the reactor or by means of an external heat exchanger and a means of pumping the reaction mixture through the heat exchanger and returning to the reactor. Improved mixing is obtainable by introducing the reactants directly into the 65 suction of the impeller of a turbo mixer. The size of the reactor is determined by the rate at which the prediluted hydrocarbon feed and acid are fed to the mixing vessel and the residence time desired. For purposes of continuous operation the reactants may enter at the bottom 70 of the reaction vessel and an overflow pipe provided at a suitable height is connected to the reactor so as to give the desired residence time. The sulfur dioxide is then re-

moved from the resulting mixture. The SO_2 is normally removed by column stripping. Only small amounts of heat are required, it is not necessary to use vacuum, but vacuum stripping can be used to advantage in speeding the operation.

The resulting mixture is then neutralized with a basic alkali metal or alkaline earth material usually aqueous or solid caustic soda or soda ash. Several stages of neutralization can be employed. This neutralization is done in the presence of a lower, i. e. C_1 to C_4 alcohol. The alcohol can be added first to quench the sulfonation reaction and the neutralizing agent thereafter added or the neutralizing agent can be added first or in the alcohol solution. The temperature should be maintained at 0°C . to $+10^\circ \text{C}$. until the mass is neutralized, then the temperature can be allowed to rise to room temperature to aid in the separation of the layers, etc. The quantity of alcohols used may vary from 50 to 150 vol. percent based on the volume of feed stock but usually 80 to 100 vol. percent is used. This is on the basis of 100% alcohol. Absolute alcohol is not used in view of using aqueous neutralizing agents.

Depending upon the sulfonate to oil ratio, the sulfonates are recovered from the neutralized mass either by treating the whole mass with a hydrophobic organic solvent or by recovering a crude alcoholic soap solution and treating the solution with the solvent. When the sulfonate to oil ratio is above 1 to 4 it is preferred to recover the sulfonates directly from the whole neutralized reaction mass. It is important that the amount of sulfonate in the solution to be extracted not exceed 20 gms./100 ml. and it is preferred to maintain this concentration below 5 gms./100 ml. The alcoholic solution of mixed sulfonates or the neutralized reaction mass is extracted by contacting with an organic solvent, e. g. benzene. It is essential that the concentration of sulfonate in the solvent be maintained below 1 gm./100 ml., preferably below 0.5 gm./100 ml. This minimizes the cosolubility of the water soluble sulfonates in the oil soluble sulfonate solution in the extraction solvent.

It is to be appreciated that equilibrium of the sulfonates between the alcohol and solvent phases must be avoided. It is also essential that the temperature during extraction be maintained above 125°F . The solvent and alcohol phases are separated and recovered.

It is an important feature of this invention that when the whole neutralized reaction mass is treated with hydrophobic organic solvent a finished oil soluble sulfonate product can be obtained that is suitable for commercial sale. This product is substantially free of inorganic salts and contains as diluent oil the unreacted oil from the original sulfonation feedstock.

Suitable hydrophobic organic solvents comprise benzene, xylenes, carbon tetrachlorides, Freons, etc. Especially preferred are single ringed aromatics particularly benzene.

The conversion of the alkali sulfonate salts to alkaline earth salts such as calcium or barium or magnesium is not an intrinsic part of this invention, and has been adequately described in the prior art, e. g. for purposes of reference see U. S. Patent No. 2,532,997. The alkali salts are, in general, converted in oil solution by a double decomposition reaction to the corresponding alkaline earth salts when it is desired to use the latter in lubricating oils.

The following examples further illustrate and demonstrate the advantages of this process.

EXAMPLE 1.—EFFECT OF ACID CONCENTRATION

Table I shows the effect of oleum dump on sulfonate yield and distribution of sulfonates when Necton 60, a 500 SSU/100 extracted Coastal Stock is treated by the above process.

Table I.—Low temperature sulfonates of Necton 60—Sulfonate yields and distribution

Percent/v. Oleum (30%)	Total Sulfonate		Benzene Solu- ble Sulfonate		Alcohol Solu- ble Sulfonate		Percent/v. Neutral Oil Yield
	Yield, percent/v.	Ashed Com- bining Weight	Yield, percent/v.	Ashed Com- bining Weight	Yield, percent/v.	Ashed Com- bining Weight	
5							
10							
15							
20							
25							
50							
15	12.7	465	11.3	494	1.4	289	87.4
10	21.4	437	17.4	512	4.0	273	82.5
15	23.8	400	18.0	482	5.8	264	79.2
20	24.6	393	15.6	513	9.0	275	77.8
25	23.1	394	15.1	488	8.0	285	76.2
50	22.8	324	8.7	497	14.0	262	79.6

This shows that regardless of the quantity of 30 wt. percent oleum used the total sulfonate produced is a mixture of oil and water soluble sulfonates of relatively low molecular weight. However, by the new process taught in this invention a maximum yield of high molecular weight oil soluble sulfonate is obtained when using 15 vol. percent of oleum, by far the more desirable product.

EXAMPLE 2.—COMPARISON HIGH AND LOW TREATING TEMPERATURE SULFONATION

Table II presents data showing the sulfonate yield and distributions on Necton 60 treated in a single 5% dump (a) at -10°C . temperature, (b) 70°C . with neutralization of the entire reaction mass, (c) conventional 70°C . treatment and acid oil sulfonate yield.

Table II.—Sulfonation of Necton 60—Comparison -10°C . and 70°C . treating temperature

Treating Temperature, $^\circ \text{C}$	Recovery Basis		Sulfonate Production and Distribution	
	Total Emulsion	Acid Oil	Total Emulsion	Acid Oil
Treating Temperature, $^\circ \text{C}$				
Percent/v. Oleum Treat BOD ¹	-10	70	-10	70
Percent/v. Sulfonate Yields BOD ¹	5	5	5	5
Total Sulfonate Recovered	12.7	9.8	3.9	3.9
Benzene Soluble Sulfonate	11.3	8.0	3.9	3.9
Alcohol Soluble Sulfonate	1.4	1.8	-----	-----
Combining Weights, NaRSO_3 Ashed:				
Total Sulfonate	465	441	506	506
Benzene Soluble	494	501	506	506
Alcohol Soluble	313	297	-----	-----

¹ BOD—Based on distillate.

This shows that when the feed stock is treated at -10°C . and conventionally neutralized a larger yield of higher molecular weight can be obtained than when treated at 70°C . A 200% higher yield of sulfonate of equal quality may be had by extracting the total emulsion rather than the acid oil layer. On the other hand if the extraction process is not used the sulfonate obtained from the total emulsion would be of inferior quality.

EXAMPLE 3

In a typical low temperature process, 1000 ml. of a solvent refined coastal lubricating oil stock having a viscosity of 840-520 SSU/100° F. were diluted with 1000 ml. of liquid SO_2 . 150 ml. of 30% oleum are added maintaining the temperature at -10°C . This reaction mixture has a mol ratio of approximately 5 mols of SO_3 /mol of sulfonatable hydrocarbon. Agitating for one hour, the SO_2 was removed by vacuum stripping still maintaining the temperature at -10°C . The total reaction mass is quenched with approximately 5200 ml. of 50% isopropyl alcohol and neutralized with 290 ml. of 50% NaOH and 600 ml. saturated Na_2CO_3 solution maintaining the temperature below -10°C .

The separated layers had the following volumes:

	Ml.
Mineral oil	792
Alcoholic soap solution	4985
Salt layer	1850

The alcoholic soap solution contained 5.02 gm. total sulfonate/100 ml. having an average molecular weight of 400 and 0.48 gm. oil/100 ml.

Twelve hundred milliliters of crude alcoholic soap solution were countercurrently fractionated in an extractor. Of the 60.2 gms. total sulfonate charged 18.0 vol. percent based on original oil feed were oil soluble sulfonates (482 M. W.) and 5.8 vol. percent were water soluble sulfonates (M. W. 264). The neutral oil yield was 79.2%.

Example 3 presents a value that is had by extractive processing. For example, by conventional treating operations a sulfonate of low molecular weight (400) may be obtained which is considered of inferior quality as a lube oil additive. However, by employing the extractive feature taught in this invention the inferior sulfonate can be refined and a sulfonate of high quality obtained.

Similar results were obtained with other feed stocks such as phenol extracts of lubricating oils and C₁₂ polypropyl benzene alkylates.

The process of this invention obtains oil soluble sulfonate yields of 50 to 100% higher than those obtained by comparable processes. Improved recovery of both the water and oil soluble sulfonates are obtained because of the prevention of emulsion formation and product degradation. It should be emphasized that all of the factors involved in the combination process contribute to these improvements.

The oil soluble sulfonates produced in the present process are substantially free from water soluble or sludge type sulfonates always found in conventional mahogany sulfonate products. This makes them particularly useful in applications where traces of these impurities are highly undesirable, for example, the present sulfonates make excellent engine detergents and rust preventives.

It is to be understood that the invention is not limited to the specific examples which have been offered merely as illustrations since modifications may be made without departing from the spirit of this invention.

What is claimed is:

1. A process of preparing and recovering superior oil-soluble sulfonates in increased yields which comprises contacting a petroleum hydrocarbon oil feed stock dissolved in liquid sulphur dioxide at a maximum temperature of -10° C. with concentrated sulfuric acid in a single treat, removing the sulfur dioxide, neutralizing the resultant total mixture in the presence of 50-150 volume percent based on the feed stock of a C₁-C₄ alcohol with an alkali agent thus forming a product emulsion, 10 countercurrently fractionating the total product emulsion in the presence of a hydrophobic organic solvent extractant capable of selectively extracting oil-soluble sulfonates in an extraction zone at a temperature above 125° F., forming and recovering an extract phase containing oil-soluble sulfonates of high quality.
- 15 2. A process in accordance with claim 1 wherein 10-25 volume percent of oleum is employed as the sulfonating agent.
- 20 3. A process in accordance with claim 1 wherein a neutralization is conducted at a temperature in the range of 0 to +10° C.
